UNITED STATES PATENT OFFICE

161,683

CONDIMENT SHAKER

Ellis F. Ellis, Akron, Ohio, assignor to Coventry Ware, Inc., Barberton, Ohio, a corporation of Ohio

Application May 3, 1950, Serial No. 9,690

Term of patent 7 years

(Cl. D44—22)

To all whom it may concern:

Be it known that I, Ellis F. Ellis, a citizen of the United States, residing at Akron in the county of Summit and State of Ohio, have invented a new, original, and ornamental Design for a Condiment Shaker, of which the following is a specification, reference being had to the accompanying drawing, forming part thereof.

Fig. 1 is a top view of the shaker showing the design;

Fig. 2 is a side view;

Fig. 3 is a front view;

Fig. 4 is a back view; and

Fig. 5 is a bottom view.

I claim:

The ornamental design for a condiment shaker, as shown and described.

ELLIS F. ELLIS.
